UNITED STATES PATENT OFFICE.

SAMUEL E. MOSHER AND LABAN B. LYONS, OF CHILlicothe, OHIO.

CAR-BRAKE.

SPECIFICATION forming part of Letters Patent No. 328,963, dated October 27, 1885.

Application filed April 7, 1883. Serial No. 90,914. (No model.)

To all whom it may concern:

Be it known that we, SAMUEL E. MOSHER and LABAN B. LYONS, citizens of the United States, residing at Chillicothe, Ross county, 5 Ohio, have invented new and useful Improvements in Railway-Car-Brake Mechanisms, of which the following is a specification.

Our invention relates to railway-car-brake mechanism, and is in the nature of an improvement upon that for which we have already filed an application for Letters Patent, based upon the principle of utilizing the weight of the car itself as a regulator of the braking force, and embodying a form of mechanism 15 consisting, essentially, of a system of leverage fulcrumed upon the spring-shelf and operated by a chain operating over a friction-pulley pivoted upon the cross-beam of the truck. In such former application the brake itself was 20 a horizontal bar arranged above the wheels and acting vertically.

The object of our present invention is the application of the essential principle described in said former application to the ordinary 25 form of brakes hung at the sides of the wheels and acting horizontally; and it consists in the combination and arrangement of parts herein more fully described.

Mechanism embodying our invention is illustrated in the accompanying drawings, in which—

Figure 1 is a plan diagram view of the spring-shelf of a car-truck, showing the arrangement of the main levers and the draft-chain connection. Fig. 2 is an end view of the car-truck, showing the arrangement of the main levers and the draft-chain connection. Fig. 3 is a side view of the truck, showing the arrangement of the bell-crank brake-levers. Fig. 4 is a cross-section of the truck-frame, swinging bolster, and spring-shelf, showing the attachment of the friction-pulley for the draft-chain; Fig. 5, a plan diagram of a car-truck, showing a modified form of mechanism applicable to 40 brakes arranged at the extreme outer sides of the contiguous truck-wheels. Fig. 6 is an end view of the same truck, showing the main levers and their actuating bell-crank connections; and Fig. 7, a side view of the truck 45 cross-sectioned through the frame and movable bolster and spring-shelf, showing the bell-crank connections with the brake-beams.

The parts described herein are indicated on the drawings by letters of reference.

W W designate the wheels of the truck; R 55 R, the cross-beams of the frame; S, the swinging bolster, and s the spring-shelf, all constructed and arranged in the usual manner.

Upon the spring-shelf s we arrange two levers, A A, longitudinally with the shelf, and 60 securely fulcrumed thereon by links or brackets a. To the inner ends of the levers A, which are contiguous, a chain, P, is attached by its two ends, passing thence upward and over two grooved friction-rolls, CC, pivoted in brackets 65 secured to the under side of the cross-beams R R, as shown in Fig. 2. In the bight of the chain the connection is made with the rod b or piston of the air-cylinder by means of an equalizing friction-roller, E, by which arrangement of parts the horizontal movement of the rod or piston b lifts the inner ends of the levers A and depresses the outer ends of the same. The outer ends of the levers A are connected by links e with the horizontal arms of bell-crank levers B, swung in pivotal bearings to 75 the under side of the cross-beams R R, there being one bell-crank arranged for each wheel, carrying a pivoted brake-shoe, B', at the extremities of the vertical arms. Thus the depression of the outer ends of the levers A carries down the horizontal arms of the bell-cranks B and forces the vertical arms carrying the brake-shoes against the wheels.

It will be readily obvious that no greater 85 force can be applied to the brakes than would be sufficient to lift the car since any such excess would expend itself in lifting the spring-shelf s through the lever A and its connection with the spring-shelf.

In the case just described, the brakes are arranged between contiguous wheels acting outwardly; but as brakes are often arranged at remote sides of contiguous wheels acting inwardly or toward each other a modification 95 in the arrangement of the mechanism is necessary. A preferable arrangement is shown in Figs. 5, 6, and 7, in which a brake-chain, N, (corresponding with P of Fig. 1, and similarly operated,) passes between two vertically-pivoted friction-pulleys, M M, arranged upon the upper side of the cross-beam R, extending thence outward, and connected at its ends with bell-crank levers L, pivoted horizontally at 100

each end of the frame between the cross-beams R R, beyond the swinging bolster S. The horizontal arms of the bell-cranks L are connected by short links or chains d, with the outer 5 ends of levers F, fulcrumed upon the spring-shelf. The latter are constructed and arranged in all respects as the levers A, before described. At the inner contiguous ends of the levers F connection is made with two bell-crank levers, 10 G G, pivoted centrally one to the under side of each cross-beam R R, and the outer ends of these bell-cranks are connected by rods H centrally with the brake-beams K. The latter are arranged in the usual manner and re- 15 quire no description. In this form of mechanism the power is applied in substantially the same manner as first described, the changes being merely of arrangement, caused by the different position of the brakes.

Having described our invention, we claim 20 and desire to secure jointly by Letters Patent—

1. The combination, in railway-car brake mechanism, of levers A, pivoted to the spring-shelf, and bell-crank brake-levers hung to the cross-beams, connected and operated substantially as and for the purpose specified. 25

2. The levers A, pivoted to the spring-shelf s, and bell-crank brake-levers B, in combination with the chain P, pulleys C C and E, substantially as set forth. 30

In testimony whereof we have hereunto set our hands in the presence of two subscribing witnesses.

SAMUEL E. MOSHER.
LABAN B. LYONS.
